UNITED STATES PATENT OFFICE.

MARTIN E. SHINN, OF CHICAGO, ILLINOIS.

CARPET-STRETCHER.

SPECIFICATION forming part of Letters Patent No. 769,328, dated September 6, 1904.

Application filed September 23, 1903. Serial No. 174,350. (No model.)

To all whom it may concern:

Be it known that I, MARTIN E. SHINN, a citizen of the United States, residing at Chicago, Cook county, Illinois, have invented certain new and useful Improvements in Carpet-Stretchers, of which the following is a specification.

My invention is an improvement in carpet-stretchers, and relates specially to the improved means for giving movement to the carpet-holding part so as to stretch the same uniformly and perfectly.

The invention is shown in the accompanying drawings, in which—

15 Figure 1 is a side elevation of the invention. Fig. 2 is an elevation from the front of the device. Fig. 3 is a sectional view. Fig. 4 is a detail. Fig. 5 is a view of a modification, and Fig. 6 shows a second modification.

20 In the figures I have shown a bar A, with a toothed or turned-over end *a*, adapted to engage some point of resistance—as, for instance, being forced into the floor or a crack in the floor. This bar is toothed on its upper 25 edge, as shown at *b*, the front walls of the teeth being concave and the rear walls straight, with the intermediate portion forming the top of each tooth. Mounted upon this bar is a bracket B, which has swiveled to it an elongated bar C, carrying a series of projecting 30 teeth or pins *c*, adapted to engage with the carpet. These pins or points extend through the bar C at an angle, as shown at Fig. 1. The bar C is swiveled to the bracket B, as shown 35 in the detail view Fig. 4, and the sectional view Fig. 3, so that the bar may be moved on its pivot *a'* to get the proper angle in case this is required to be varied. The points *c* engage the carpet, and the stretching action 40 is secured by moving the bracket B upon the bar A. This is accomplished by a screw or worm D, which is mounted upon a spindle *d*, extending from the upper part of the bracket 45 B above the position of the bar A. The worm D has a handle *e*, while the teeth of the worm engage the teeth of the rack-bar A. As the handle *e* is turned the worm engaging the teeth on the bar moves the bracket B, gradually stretching the carpet by reason of the engagement therewith of the points *c*.

In Fig. 5 I have shown a modification in which instead of the swiveled construction shown in Fig. 1 I have shown the bracket B, with a projecting point *b'*, and one or more of these may be provided integral with the bracket. In other respects the construction and operation are the same.

In Fig. 6 I have shown a further modification, and in this I provide an eccentric clamp, with a serrated face, and thus through the medium of a plate *d'* the material to be stretched is clamped to the lower face of the bracket B, and a stretching action is secured by the action before described.

It will be seen that by the peculiar shape of the handle it does not in use project forward of the screw or worm D, but is in rear thereof, so that it does not offer an obstruction to the near approach of the stretcher to the wall, and thus the carpet can be drawn much closer to the wall than in any other construction with which I am familiar. The stretching is very gradual and may be stopped or interrupted at any point.

What I claim is—

75

1. A carpet-stretching device comprising a rack-bar, a bracket, carpet-engaging means carried by the bracket, a rearwardly-extending projection on said bracket, a worm journaled on said projection and engaging said rack-bar, and a handle for rotating said worm, said handle being at all times during its rotation in the rear of said projection, substantially as described.

2. A carpet-stretching device comprising a rack-bar, a bracket, carpet-engaging means carried thereby, a projection on said bracket, a worm journaled on said projection at an angle to said rack-bar, and means for rotating said worm, said rotating means being at all times in the rear of said worm, substantially as described.

20 In testimony whereof I affix my signature in presence of two witnesses.

MARTIN E. SHINN.
